UNITED STATES PATENT OFFICE

2,438,865

RAPID ELECTRIC FLUID HEATER

Leonard A. Rehard, Kansas City, Mo.

Application April 6, 1946, Serial No. 660,123

1 Claim. (Cl. 219—39)

1

My invention relates to improvements in heating units, particularly well adapted for heating fluids for such uses as may be desired.

One of the objects of my invention is the provision of a novel heating unit of the kind described which will heat a desired fluid, and is provided with novel means by which the heated fluid may be withdrawn at different desired temperatures.

Still another object of my invention is the provision of a novel heating unit of the kind described, which is simple, cheap, strong, durable, not likely to get out of order, and which is efficient in its operation.

The novel features of my invention are herein-after fully described and claimed.

In the accompanying drawings, which illustrate a preferred embodiment of my invention,

Fig. 1 is a horizontal section, on the line 1—1 of Fig. 2, of my improved heating unit.

Fig. 2 is a central vertical sectional view of the heating unit, some parts being shown in side elevation.

Fig. 3 is a top view of the heating unit.

Fig. 4 is a side elevation of the heating unit.

Fig. 5 is a central vertical sectional view of one of the valved tubes for withdrawing heated fluid from the unit.

Fig. 6 is a side elevation of the lower portion of one of the concentric tubes.

Similar characters of reference designate similar parts in the different views.

In the preferred embodiment of my invention, illustrated in the drawings, my improved heating unit is provided with a plurality of vertical cylindrical tubes, disposed concentrically in each other, and of like length, and respectively designated by 1, 2, 3 and 4.

5 and 6 designate respectively an upper circular head and a lower circular head, said heads on their inner sides being provided with concentric grooves 7, Fig. 2, in which are respectively tightly fitted the adjacent ends of the tubes 1, 2, 3 and 4.

The lower head 6 is provided with supporting legs 8, and a central vertical circular hole 9, Fig. 2.

Bolts 10 having nuts 11 extend vertically through the heads 5 and 6 and hold the heads tightly against the ends of the vertical tubes 1, 2, 3 and 4.

The heads 5 and 6 and the tubes 1, 2, 3, and 4 form concentric chambers 12, 13, 14 and 15.

A fluid discharge pipe 16 extends vertically in the chamber 15 and has its externally threaded upper end fitted in a central hole in the upper head 5, its lower end being above and spaced from

2

the hole 9 in the lower head 6. A discharge pipe 17 mounted on the upper head 5 and having in it a valve or damper 18, registers with the pipe 16.

Bolts 19 having nuts 20 extend through the 5 lower head 6 and a circular nonconducting plate 21, preferably of asbestos, and fastens the plate 21 to the under side of the head 6. A vertical tubular container 22, mounted on the plate 21, extends upwardly through the hole 9 into the pipe 10 16, and holds an electrical heating element 23.

The outermost tube 1 has near the head 6 an inlet fluid passage 24, containing a valve or damper 25.

The tube 2 has through it adjacent to the upper head 5 fluid passages 26, circularly spaced apart, and connecting the chamber 12 with the chamber 13.

The tube 3, adjacent to the lower head 6 has through it circularly spaced apart fluid passages 20 27, which connect the chamber 13 with chamber 14.

The tube 4 has through it adjacent to the upper head 6 circularly spaced apart fluid passages 28, which connect the chamber 14 with the central chamber 15.

The upper head 5 is provided with threaded holes respectively registering with the chambers, 12, 13 and 14, and in which are respectively fitted the lower threaded ends of fluid discharge tubes 30 29, 30 and 31, respectively provided with shut off valves 32, Figs. 2, 3, 4 and 5.

In operation, fluid to be heated, as air, is admitted through the passage 24, into the outer chamber 12, from which it passes by the passages 35 26 into the chamber 13, thence passing downwardly to and through the passages 27 into the chamber 14, thence upwardly to and through the passages 28 to the central chamber 15, thence downwardly to the lower open end of the pipe 16, 40 thence upwardly through the pipe 16, and past the heating element container 22, and out from the pipe 17, to the atmosphere, or where it is to be used.

The fluid passing from the pipe 16 is at its 45 maximum heat. If it is desired to get fluid somewhat cooler, fluid is drawn from the discharge pipe 31. If fluid of still lower temperature is desired, it is drawn from the discharge pipe 30. If yet cooler fluid is desired, it is drawn from discharge tube 29.

Thus fluid of different temperatures may be drawn from the same unit at the same time.

Many modifications of my invention, within the scope of the appended claim, may be made without departing from the spirit of my invention.

What I claim is:

In a heating unit, in combination with spaced apart tubes of different diameters one within the other, of two heads provided respectively on their inner sides with concentric grooves in which are respectively tightly fitted opposite ends of said tubes forming chambers concentrically in said tubes, means for fastening said heads to said tubes, a fluid discharge pipe extending through one of said heads into the innermost of said tubes and spaced from the other of said heads, a heating element supported by said other head in the innermost of said chambers, the outermost of said tubes having a fluid inlet passage, the inner ones of said tubes having respectively through them fluid passages connecting adjacent chambers, the

5 fluid passages of next adjacent ones of said tubes being located respectively adjacent to opposite ones of said heads, and valved fluid discharge tubes communicating respectively with different ones of said chambers.
